UNITED STATES PATENT OFFICE.

CHARLES DECRETTE, OF NEW YORK, N. Y.

PROPELLER OR BLOWER.

Application filed July 19, 1924. Serial No. 726,931.

To all whom it may concern:

Be it known that I, CHARLES DECRETTE, a citizen of the United States, residing at New York, in the county of New York and 5 State of New York, have invented certain new and useful Improvements in Propellers or Blowers, of which the following is a specification.

The main object of this invention is to 10 provide a propeller which also may be efficiently used as a blower. The device when used as a propeller decreases the head resistance to a minimum. The propeller is constructed in the form of a whirling drum 15 with blades set at a slight angle.

Another object is to provide means on the propeller or blower whereby all the blades, which are independently mounted, may have their pitch varied in unison.

20 These and other objects will become apparent in the description below, in which characters of reference refer to like-named parts in the drawing.

Referring briefly to the drawing, Figure 25 1 is a front elevational view of the device.

Figure 2 is a longitudinal sectional elevational view of the same.

Figure 3 is a rear and elevational view of Figure 1.

30 Figure 4 is a partly sectioned side elevational view of the blade adjuster ring.

Figure 5 is a front elevational view of Figure 4.

Figure 6 is a perspective view of a section 35 of the device showing the method of moving the blades.

Referring in detail to the drawing, the 40 numeral 10 indicates the circular wall of a cylinder. Said cylinder is open at both ends and at its forward end a plurality of ribs 11 extend outwardly and toward the axis of the cylinder. The adjacent ends of the ribs join each other at a common vertex, and at the latter position a sleeve 12 is fixed 45 to the ribs. The sleeve has a longitudinal opening therein in which one end of a shaft 13 is rotatably journalled; said shaft being adapted to be rotated by a source of power such as a motor, not shown, together with 50 the remainder of the device. The shaft is supported near both its ends on brackets 14 which are mounted on a frame 15, the latter serving as a support for the entire device. At the rear of the cylinder a ring 16 encircles 55 the interior of the cylinder and is per-

manently secured in place by rivets or the like. A hollow hub 17 having faces 18, is mounted on the shaft, one of said faces being removable so that the blade adjusting mechanism may be mounted in the chamber 60 19. The annular space between the ring 16 and the hub 17 is utilized by a plurality of blades 20 which are curved longitudinally and are pivoted at one end on a pin which is anchored on the hub and passes thru one 65 of the webs 21 of the blade at one corner thereof. The same web at the opposite corner has a pin 22 which extends thru a rectangular opening 23 cut into the peripheral wall of the hub. Within the chamber 70 19 of the hub, a blade adjuster ring 24 is rotatably mounted. Said ring has an internal periphery on which gear teeth 25 are formed and the external periphery has a plurality of angular channels 26 in which 75 the ends of the pins 22, which project thru the opening 23 of the hub, register. A thumb screw 27 is rotatably mounted in the outer wall 18 of the hub and has a shank thereon which passes thru said wall 18 into 80 the chamber 19 in which a pinion 28 is located. The pinion is rigidly mounted on the shank of member 27 and meshes with the teeth 25 of the blade adjuster ring 24.

In using the device as a propeller or 85 blower, the shaft 13 on which the entire device is mounted, is coupled to a motor or the like, or any device which will transmit rotation of the shaft, said means not being shown on the drawing. When using the device as a blower, air enters thru the openings between the blades 20, as the latter where they overlap each other, are spaced apart. When using this device as a blower, the opposite end of the hub would be anchored within a room or chamber, and the other end in which the blades 20 are mounted, would be exterior of the chamber or room. The amount of air drawn in by the blades may be varied thru adjustment of 90 the blades. Adjustment of the blades is accomplished by rotation of the thumb screw 27. As the pinion 28 is rigidly attached to the shank of the thumb screw and meshes with the adjuster ring 24, the latter 95 will be rotated. Each blade having a pin 22 at one of its ends engaged in an inclined channel 26 will be moved transversely or substantially parallel to the axis of the shaft 13 and thus decrease or increase the space 100 105 110

of each adjacent pair of blades, the entire blades being moved in unison by the adjuster ring 24 in either direction.

I claim:—

5 In a blower or propeller, a cylindrical body open at both ends; a plurality of blades mounted in said body, said blades being curved longitudinally to conform to the periphery of the body, the blades being normally inclined to provide a space between each pair of blades at adjacent ends, the ends of said blades overlapping in spaced-apart staggered relation, an annular hub supporting

said blades on its periphery, said hub having openings at the free ends of said blades, a pin on the free end of each blade passing thru the opening in the hub, an adjuster ring rotatable in said hub and having inclined channels formed on its periphery, the pins on the free ends of said blades being adapted to register in said channels, said ring when rotated being adapted to swing the blades about the fixed pivot, and means for rotating said adjuster ring.

In testimony whereof I affix my signature.

CHARLES DECRETTE.
